Primary Examiner — George J Ulsh*Assistant Examiner* — Jihyung Yoon*(74) Attorney, Agent, or Firm* — Lempia Summerfield Katz LLC(57) **CLAIM**

The ornamental design for a urinal as shown and described.

DESCRIPTIONFIG. 1 is a perspective view of a urinal;
FIG. 2 is front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The evenly-dashed broken lines in the drawings show portions of the urinal which form no part of the claimed design.
